SIGNAL SYSTEM FOR ELEVATORS

Harold W. Williams, Chicago, Ill., and William F. Eames, Pittsburgh, Pa., assignors to Westinghouse Electric Elevator Company, Chicago, Ill., a corporation of Illinois

Application August 24, 1934, Serial No. 741,271

22 Claims. (Cl. 177—336)

Our invention relates to signalling systems for elevators and more particularly to signalling systems for indicating to the car attendants the stops to be made in taking on or letting off passengers.

One object of our invention is the provision of a signalling system that is simple and efficient in operation and capable of being readily and economically manufactured and installed.

Another object is to provide for giving the attendant on a car a signal for a stop at a floor only when the car is in such position that it can be stopped at the floor for which the signal is given.

A further object is to provide for indicating to the attendant on a car the floors lying between the car and the next car ahead at which he should stop his car and to also indicate to the car attendant exactly when the car controls should be operated to effect the stopping of the car in response to the stop signals.

A further object is to provide for indicating to the car attendant, during a car stopping operation, the floor at which the stopping operation is taking place, and also to indicate, while the car is moving, the next floor at which a stop can be made.

Another object is to provide means by which the attendant on a car may set a signal for a stop at a floor which will indicate the time at which he must operate the car controls to stop the car accurately level with the floor for which the stop signal exists.

Another object is to provide a signal device for each car in a group of cars which will indicate the floors at which stops should be made and to also render each signal device effective to indicate stops only at the floors between itself and the next car ahead.

Another object is to provide an indicating device which will not only indicate the floors at which stops should be made but will also indicate the time during the car travel at which the car controls should be operated to stop the car.

A still further object is to provide a signal system which will relieve the car attendants of the necessity of remembering stops to be made and of the difficulty of making metal calculations as to when and where the car controls should be operated in stopping the car.

It is also an object to provide a signal system for a bank of elevator cars which will lessen the confusion of the car attendants by reducing the

number of active signal lamps or devices in each car.

Other objects of the invention will, in part, be obvious and will, in part, appear hereinafter. For a better understanding of the invention, reference may be had to the following detailed description in conjunction with the accompanying drawings, in which,

Fig. 1 is a diagrammatic representation of an elevator installation embodying a signal system constructed in accordance with our invention;

Fig. 2 is an enlarged view, in front elevation, of the indicator device disposed in each of the cars shown in Fig. 1;

Fig. 3 is a view, in front elevation, of the device shown in Fig. 2 with part of the front portion broken away;

Fig. 4 is a view, in side elevation of the device shown in Figs. 2 and 3.

Fig. 5 is a diagrammatic representation of the contact segments and contact brushes shown in one of the front selectors illustrated in Fig. 1;

Figs. 6, 7 and 8, collectively, constitute a straight-line diagrammatic representation of the signal and control systems for operating the cars shown in Fig. 1;

Figs. 6A, 7A and 8A, collectively, constitute an explanatory illustration of the relays in the system illustrated in Figs. 6, 7 and 8;

Fig. 9 is a modification of the wiring system shown in the upper right-hand corner of Fig. 6 or Fig. 8 for the stop call signal lamps in the cars;

Fig. 10 is a view, in front elevation, of one of the targets shown in the indicating device in Fig. 2, as modified for use with the wiring system shown in Fig. 9; and,

Fig. 11 is a view on the line XI—XI of Fig. 10.

The illustration of the relays in Figs. 6A, 7A and 8A shows their coils and contact members disposed in horizontal alignment with their positions in the straight-line circuits of Figs. 6, 7 and 8 so that the reader may readily determine the name and use of any relay, the number and kind of its contact members and the position of its coil and its contact members in the straight-line circuits.

For convenience in reading the drawings, Fig. 7 should be placed under Fig. 6, Fig. 8 under Fig. 7, Fig. 6A beside Fig. 6, Fig. 7A beside Fig. 7 and under Fig. 6A, and Fig. 8A beside Fig. 8 and under Fig. 7A.

Referring more particularly to the drawings, we have illustrated an elevator system embody-

ing the two cars A and B for serving six floors. The cars may be suitably suspended by cables 11 and 12 (Fig. 1) which pass over hoisting drums 13 and 14 respectively.

5 Although we have shown only two cars, and a signal and control system therefor, as applied to only six floors, it is to be understood that the invention may be utilized for any number of cars serving any number of floors.

10 For convenience, the main relays included in the system are designated as follows:

C=Stop signal push buttons in car A.

CC=Holding coils for stop push buttons in car A.

15 D=Down direction switch for car A.

E=High speed inductor relay for decelerating car A.

F=Intermediate speed inductor relay for decelerating car A.

20 G=Stopping inductor relay for stopping car A.

H=Inductor restoring relay for car A.

J=Stop signal push buttons at the floors.

K=Voltage relay for controlling high speed relay.

25 L=Stop call signal lamps.

M=Cancellation control relay.

N=Intermediate speed relay.

P=Car running push buttons in car A.

30 Q=Cancellation coils on floor button registering relays.

R=Stop call registering relays for floor push buttons.

S=Signal lamps for indicating when to operate car controls to stop car A.

35 U=Up direction switch for car A.

V=High speed relay for car A.

W=Up direction preference relay for car A.

X=Down direction preference relay for car A.

Z=Zoning relays, common to both cars, for

40 limiting stop call signals to nearest approaching cars.

As shown, the relays for car A are given suitable reference characters and the relays for car B are given the same reference characters as those in car A, with the letter B prefixed thereto. The letter U indicates the up direction; the letter D the down direction. The prefix numerals indicate the floors and the suffix numerals indicate the contact members of the relays.

45 50 Referring to the control system for car A, as shown in Figs. 6, 7 and 8, the hoisting drum 13 is directly coupled to an armature 17 of a suitable hoisting motor 18, the field winding 19 of which is connected for constant voltage energization to a source of supply designated by the supply conductors L+1 and L-1, (Fig. 6).

A variable voltage system of control may be provided for operating the hoisting motor 18 wherein the armature 17 is connected in a closed 55 circuit with the armature 21 of a generator 22. The generator is provided with a separately excited field winding 23 and a cumulative series field winding 24. A pair of resistors r1 and r2 are connected in the circuit of the separately excited field winding 23 for controlling the speed of the generator. The armature 21 of the generator may be driven by a suitable driving motor 25 which may be connected to a suitable source of supply, as represented by the conductors and switch 26.

70 75 A brake 5 operated by a brake magnet 6 is provided for applying a braking effect to the hoisting drum 13 when the car is brought to a stop, the brake magnet 6 being energized to release the brake 5 when the car is running and

being deenergized to apply the brake when the supply of power to the car is cut off.

The direction and speed of the hoisting motor 18 may be suitably controlled by controlling the direction and the value of the excitation current that is supplied to the separately excited field winding 23 of the generator 22.

The direction of excitation current for the field winding 23 may be suitably controlled by means of an up direction switch U and a down direction switch D, while the value of the current supplied to the field winding may be controlled by means of an intermediate speed relay N and a high speed relay V, which control the resistors r1 and r2.

The closing of the up direction and the down direction switches U and D, as well as the intermediate speed and the high speed relays N and V, may be controlled by means of any suitable car switch or car running push buttons. In the present case, we have illustrated, for convenience, an up car-running push button UP and a down car-running push button DP mounted in the car in position to be actuated by a car attendant. The push buttons UP and DP are pressed by the car attendant to start the car and as long as they are held in, they will keep the car moving. However, as soon as they are released, the close the circuit for that part of the control system which then automatically effects the stopping of the car level with the next floor.

Any suitable means or system may be employed for automatically stopping the car A level with the floors it serves. As an example of such means, I have illustrated an automatic inductor relay landing system similar to that disclosed in Patent No. 1,884,446 issued October 25, 1932, to K. M. White and G. K. Hearn, and assigned to the Westinghouse Electric Elevator Company.

The landing system for car A (Fig. 1) includes a high speed decelerating inductor relay E, an intermediate speed inductor relay F and a stopping inductor relay G for causing the car to be automatically decelerated from its high speed and brought to a stop at an exact level with the floor. The high speed decelerating inductor relay E is mounted on car A in position to cooperate with an inductor plate UE for the up direction and an inductor plate DE for the down direction. The intermediate speed inductor relay F is mounted in position to cooperate with an inductor plate UF for the up direction and an inductor plate DF for the down direction. The stopping inductor relay G cooperates with an inductor plate UG for the up direction and an inductor plate DG for the down direction. The inductor plates are constructed of magnetic material and are mounted in the hatchway in such position as to cooperate with and open the contact members of the inductor relays on the car when the relays are in an energized condition as the car approaches a stop at a landing.

For simplicity, only one set of inductor plates for one floor have been shown, but it will be understood that a set similar to that shown may be provided for each floor served by the car intermediate the upper terminal landing and the lower terminal landing. A set of inductor plates corresponding to the inductor plates UE, UF and UG may be provided for the upper terminal floor and a set corresponding to inductor plates DE, DF and DG may be provided for the lower terminal floor.

As shown, each inductor relay is provided with two sets of contact members. For an "up" stop, 75

the contact members **E1** of the relay **E** cooperate with the inductor plate **UE**, the contact members **F1** cooperate with the inductor plate **UF**, and the contact members **G1** cooperate with the inductor plate **UG**. For the down direction, the contact members **E2** of relay **E** cooperate with the inductor plate **DE**, the contact members **F2** with the inductor plate **DF** and the contact members **G2** with the plate **DG**.

10 The contact members of the inductor relays just described are so connected with the car control circuits that, when the inductor relays are energized to decelerate and stop the car at the floor represented by the inductor plates in

15 the down direction, the contact members **E2** pass the inductor plate **DE** and are thereby opened to decelerate the car from high speed, as the contact members **F2** come opposite the inductor plate **DF** they open to decelerate the car from

20 intermediate speed, and as the contact members **G2** come opposite the inductor plate **UG**, they open to stop the car level with the floor. The contact members **E1** of relay **E**, **F1** of the relay **F** and **G1** of relay **G** are opened by the inductor plates **UE**, **UF** and **UG**, respectively, when the stop is to be made in the up direction.

The inductor relays are of the self-holding type, that is, when they are energized but have not yet come opposite an inductor plate, the contact members remain closed, but when the relay comes opposite an inductor plate, the contact members adjacent that plate move to their open position and are held in such open position until the inductor relay is deenergized. The means for holding the contact members in the open position on inductor relay **E** are the extended portions **28** and **29** (Fig. 1).

For instance, it will be seen that when the inductor relay **E** passes the down inductor plate **DE** in an energized condition, the contact members **E2** are opened by the arm **29a** moving upwardly to a position where it is attracted and held by the magnetized projection **29**. Therefore, the opened contact members remain open and do not, after passing the inductor plate, reclose to complicate the operation of the control system. However, I do not desire to be limited to inductor relays of this particular type because inductor relays with temporary opening contact members which are well known in the art may be used just as readily if the motor control system is adjusted to cooperate with them.

The exact position of the inductor plates in the hatchway and of the inductor relays on the cars cannot be here given because the position of these devices varies in each installation by reason of differences in hoisting motors, weight of cars, height of ceilings, etc. However, in the many commercial installations of inductor stopping systems already made, it has been found that the mechanics have no difficulty in ascertaining while the cars are first tried out in operation, just the precise positions in which the plates and relays should be placed.

In the present system with the cars operating at a speed of approximately 600 feet per minute, it will probably be found satisfactory to so locate the inductor plates that the car will start to decelerate from high speed at about eleven feet from the floor, to start decelerating from intermediate speed at about six feet from the floor, and to start decelerating from stopping speed to a dead stop at about one and one-half inches from the floor. In locating the inductor plates,

due allowance must be made for the position of the cooperating inductor relays on the car.

In view of the fact that the energized inductor relays remain energized after their contact members are operated by passage near the inductor plates, an inductor restoring relay **H** (Fig. 6) is provided for deenergizing the inductor relays of car **A** after a stop has been made and also for so interlocking them that they can be energized only while the car is moving.

The automatic inductor stopping system comes into action in the present case at about eleven feet from the floor at which the stop is to be made. This eleven feet may be called the decelerating zone. Hence the release of the car running button to throw the automatic stopping system into action must take place before the car reaches that eleven foot distance from the stop. If the button is released when the car is closer than eleven feet to the next floor, the automatic stopping system will not stop the car at the floor but will stop it at the next floor beyond. Therefore, we have an attendant's response zone of about one floor distance preceding each decelerating zone in which the car running button may be released to cause the automatic stopping system to come into operation as the car enters the decelerating zone and thereby make the stop desired.

As shown, the car **A** is started and kept running by pressing the up running button **UP** or the down running button **DP** and is stopped by releasing the pressed running button. Therefore, when a stop is to be made at a floor, it is desirable to have some means by which the attendant in the car may know just when to release the running button, that is, when he is in the attendant's response zone, in order to effect the stopping of the car at the floors where passengers desire to enter and leave the car.

In order to accomplish this purpose, we have provided an indicating device **50** in car **A** and an indicating device **B50** in car **B**, (Fig. 1).

As shown in Figs. 2, 3 and 4, the indicating device **50** comprises a box or frame **51** provided with a face plate **52**. The frame **51** may be mounted in any suitable position in the car in which the face plate **52** will be in front of the car attendant so that the attendant may readily observe the condition of signals thereon during his operation of the car. A double column of signal targets **53** is disposed in the face plate **52** (Fig. 3). Each of the targets comprises a small rectangular piece of translucent glass or some similar substance which may be illuminated for signal purposes. Behind each target is disposed a suitable incandescent lamp bulb **54** (Fig. 3), the light of which is restricted by means of suitable walls **55** to the target with which it is associated to thereby illuminate only that target.

Referring now to Fig. 2, the targets and their illuminating incandescent lamp bulbs in the right-hand column comprise stop call signal lamps and are given the reference characters **1L**, **2L**, **3L**, **4L**, **5L**, and **6L**, corresponding respectively to the first, second, third, fourth, fifth and sixth floors. These call signal lamps provide means for notifying the car attendant as to the floors at which passengers desire to get on or off the car. That is, when one of the call signal lamps is lighted, it means that a stop should be made at the corresponding floor.

The targets with their incandescent lamp bulbs in the left-hand column comprise stop position signal lamps and are given the reference char-

- acters **1S**, **2S**, **3S**, **4S**, **5S** and **6S**, corresponding to the first, second, third, fourth, fifth and sixth floors, and, as shown, each of these signal lamps has on it the number of its floor. These stop 5 position signal lamps provide means for indicating to the car attendant as he approaches a floor when he should release the car running button to effect the stopping of the car at that floor. This notification is given as the car approaches each 10 floor, regardless of whether or not the car is to stop at that floor. Also, when a car stops and stands at a floor the indicating lamps indicate the floor at which the stop is being made. Therefore, the lamps **1S**, **2S**, **3S**, etc., may be called stop 15 position lamps because they continually indicate the floor at which the car is in position to stop or the floor to which the car is decelerating to a stop or the floor at which the car is stopped and standing.
- 20 The zone in which the car running button must be released, as indicated by the stop position lamp, to cause the automatic inductor system to decelerate and stop the car at a floor may be called the attendant's response zone, and comprises 25 a zone of approximately one floor height in length preceding the location of the initial deceleration point for the associated floor.

The two columns of signal lamps are side by side, the one column notifying the attendant the 30 floors at which stops should be made, and the other column indicating the periods during car travel in which the car running button should be released to make a stop the floor for which a stop is being made and the floor at which the 35 car is standing. Therefore, when two side-by-side signal lamps are illuminated simultaneously, that is a signal to the car attendant to release the car running button for a stop.

The indicating signal lamps **1S**, **2S**, etc., do not 40 show exactly the position of the car in its hatchway but they do show the position of the car with respect to its ability to stop at a floor. For instance, if the car A is standing at the third floor, the third floor indicating signal lamp **3S** is illuminated. If the car starts in the up direction, the fourth floor indicating lamp **4S** will come on at once and the third floor signal lamp **3S** will go out. As soon as the car attains such speed that it can no longer stop at the fourth floor, (the 50 car will be about half-way between the third and fourth floors), the fourth floor lamp will go out and the fifth floor signal lamp **5S** will come on. If a stop call is registered for the fifth floor, the call signal lamp **5L** will be illuminated, and when 55 the two signal lamps **5L** and **5S** opposite one another are lighted simultaneously, the running button should be released to make the stop.

When the car starts to slow down for the fifth floor, the fifth floor indicating lamp **5S** will be held lighted while the car slows down and comes to rest at the fifth floor, and also stays lighted until the car starts away from the fifth floor.

It is desirable to have some means whereby 60 waiting passengers at the various floors may operate the stop call signal lamps **1L**, **2L**, etc. Therefore, the stop call signal lamps **1L**, **2L**, etc. in each car may be operated by push button switches disposed at the floor landings in position to be operated by the waiting passenger at the 70 landings. The floor push buttons (Fig. 7) are designated as **1UJ**, **2UJ**, **3UJ**, **4UJ** and **5UJ** for the up direction at the first, second, third, fourth and fifth floors and as **6DJ**, **5DJ**, **4DJ**, **3DJ** and **2DJ** for the down direction at the sixth, fifth, fourth, 75 third and second floors.

The floor push buttons are common to both cars; that is, there is only one button for each direction at each floor regardless of the number of cars and a waiting passenger needs to press only one button for the direction in which he desires to go in order to operate the stop signal in the nearest approaching car for that direction. Associated with the floor push buttons are stop call registering relays **1UR**, **2UR**, **3UR**, **4UR** and **5UR** for the up direction and **6DR**, **5DR**, **4DR**, **10 3DR** and **2DR** for the down direction. Each of these relays operates to maintain its floor button circuit in its completed condition after its button is pressed until the stop signal thereby registered is cancelled by a car answering the call. 15

With this system, the temporary operation of a floor button will register or, in other words, initiate and maintain a circuit which will light the corresponding stop call signal lamp in the nearest approaching car for that floor in the 20 direction corresponding to the operated button, and it will not be necessary to continue pressing the button after it is once operated to maintain the stop signal in the car.

By the term "nearest approaching car", we mean 25 that car whose direction of travel and distance from said floor will permit the car stopping system (inductor relays, etc.) to stop it at that floor when it arrives thereat. In other words, it means the car which is still capable of being stopped at 30 the floor at which the stop call is registered at the time the call is registered.

A cancellation coil is wound on each registering relay in opposition to the registering coil. When a car answers a registered floor call, it energizes 35 the cancellation call corresponding thereto and thereby overcomes the energization of the registering coil, thus cancelling the call. The cancellation coils are designated as **1UQ**, **2UQ**, **3UQ**, **4UQ** and **5UQ** for the up direction and as **6DQ**, **5DQ**, **40 4DQ**, **3DQ** and **2DQ** for the down direction.

A plurality of signal push buttons are also provided in each car whereby the attendant in that car may operate the stop call lamps in his own car, but not the other car, to indicate the various floors at which he should stop to let off passengers. The signal push buttons in car A are designated as **2C**, **3C**, **4C** and **5C**. No car buttons are needed for the terminals because the stops at the terminals are made automatically. 50 For convenience, the signal buttons in car A are mounted in a vertical row beside the signal lamps and the car-running buttons are mounted below the signal lamps in the face plate **52**.

Associated with the respective car push buttons for car A are holding or registering coils **2CC**, **3CC**, **4CC** and **5CC**. These coils operate to hold the car push buttons in a depressed position after they are pressed by the car attendant, to maintain the stop signal lamps in their lighted condition. The registering coils are automatically deenergized when the car reaches the terminal floors to release the buttons for the next direction of operation. Therefore, when the car attendant presses a car button, he may be said 60 to "register" a stop call signal on the stop call signal lamps in the same manner as a stop call is registered by the floor buttons. By "registering" a stop call, we mean the act of initiating and maintaining a circuit which will maintain 70 the lamp in its lighted condition until the car reaches its terminal floor.

The stop position indicating lamps are operated by suitable contact brushes on a floor selector to be hereinafter described. 75

Although our improvement may provide for lighting the stop call signal lamps in all cars approaching a floor at which a floor button has been pressed, it is unnecessary as only the nearest car will answer the call. Therefore, we have provided a means whereby the pressing of a floor push button will light the corresponding stop call signal lamp in only the nearest car approaching in the desired direction and leave the stop call signal lamps for the same floor in the other cars unlighted. In other words, we have provided for so zoning the stop call signal lamps that only the stop call signal lamps in the nearest approaching car will be lighted in response to the registration of a stop call, thereby saving the unnecessary operation of many lamps. It is obvious that if the nearest approaching car will answer the call, the lighting of the stop call signal lamps in the other cars is unnecessary.

In order to accomplish this zoning purpose, we have provided a plurality of zone relays (Fig. 7) designated as 2UZ, 3UZ, 4UZ and 5UZ for the up direction and as 5DZ, 4DZ, 3DZ and 2DZ for the down direction. The zone relays are common to both cars and are operated in accordance with the position of the cars.

In order that certain circuits may be conditioned for operation only when car A is moving upwardly and other circuits may be conditioned for operation only when car A is moving downwardly, we have provided an up direction preference relay W and a down direction preference relay X, (Fig. 6), which relays operate in accordance with the direction of operation of the car. The direction preference relays may be operated in any suitable manner. In the present case, they are illustrated as operated by both limit switches ULS and DLS and the direction switches U and D.

In order that the various circuits for the push buttons, stop call lamps, zone relays, stop position indicating lamps, etc., may be connected in accordance with the position of the cars with respect to the floors past which they operate, the car A is provided with a floor selector SE and the car B with a floor selector BSE. The floor selectors may be of any suitable type such as are usually employed in elevator systems and may be located at any suitable point such for example as in the penthouse or in the elevator shaft.

The floor selector SE for car A (Figs. 1 and 5) is provided with a set of "up" contact segments and a set of "down" contact segments arranged according to the floors and disposed to be engaged by cooperating brushes 30 to 37, inclusive, for the up direction and 40 to 47, inclusive, for the down direction. The brushes are mounted upon and insulated from a movable arm SM.

The movable arm is operated in accordance with the movements of the car by means of a screw shaft 15 that may be driven by some part of the operating mechanism of the car, for instance by a shaft 16 connected to the hoisting drum 13. The frictional engagement between the arm SM and its operating screw 15 will cause the arm to bear upon the "up" contact segments when the car is traveling upwardly and upon the "down" contact segments when the car is traveling downwardly. It will be understood that the arm will tilt from one side to the other when the direction of operation of the car is reversed.

However, in the present system when the car is at a terminal, it is desirable to have the arm SM tilt to the opposite direction as soon as the

car is in condition to travel in the opposite direction, without waiting until the car actually begins to move. For this purpose, each floor selector is provided with a pair of electromagnets which tilt the floor selector arm for the up direction when the car is at the lower terminal upon the car's "up" switch being closed and to tilt the selector arm to the down direction when the car is at the upper terminal upon the car's down switch being closed. The electromagnets 10 on the floor selector SE (Fig. 1) are designated as 48 for the up direction and 49 for the down direction.

The group of up contact segments designated as a under the advance brush 30, the intermediate brush 31 and the standing brush 32 are provided for energizing the stop position indicating lamps as the car moves from floor to floor.

The group of up contact segments designated as b under the brush 33 are provided for energizing the stop call signal lamps when stop calls are registered for the various floors. The brush 33 is made thick enough to bridge the gap between the contact segments to maintain the constant lighting of any lamp for which the circuit has been closed.

The group of up contact segments c under the brush 34 are provided for energizing the zone relays 2UZ, 3UZ, etc. in accordance with the position of the car. The brush 34 is made thick enough to bridge the gap between adjacent contact segments so that some one of the zone relays will always be energized.

The group of up contact segments designated as d under the forward brush 35, the middle brush 36, and the stopped brush 37 are provided for energizing the cancelling or restoring coils 1UQ, etc., when a stop is made in answer to a registered call.

The contact segments on the down side of the floor selector are engaged by the down brushes 42 to 47, inclusive, when the car is descending and correspond to the contact segments just described for the up direction, those marked e being for the stop position indicating lamp segments, f the stop call lamp segments, g the down zone relay segments and h the cancellation coil segments.

The floor selector BSE for car B is similar to the one described for car A and inasmuch as the control system for car B is similar to that just described for car A, a detailed description of the control system for car B is omitted.

The spacing and positioning of the contact segments on the floor selectors are an old art and it is well known that the position of the contact segments and the contact brushes cannot be selected until the height of a building, the distances between floors, etc., for a given installation are known. After these details are supplied, any mechanic acquainted with the art will be able to satisfactorily locate the contact segments and brushes for connecting the circuits of the cars in accordance with the floors past which they operate.

A relay M is connected in parallel with the high speed decelerating relay E to so control the cancellation brushes 35, 36, 37 and 45, 46 and 47 that a registered call will be cancelled as soon as a car-running button is released to answer the call and to keep the call cancelled and thereby prevent the registration of another call on the same button until after the car completes its call and leaves the floor.

A voltage relay K is connected across the circuit between the generator 22 and the motor 18

75 75

and provided with contact members **K1** in the circuit of the high speed relay **V**. The relay **K** prevents the high speed relay **V** from becoming effective after the motor starts until the voltage rises to a predetermined value.

The invention may be understood more clearly by the following assumed operation of the apparatus illustrated in the drawings.

It will be assumed that the switches **27**, **26** (Fig. 6) **B26** (Fig. 8) and **38** (Fig. 7) are closed to prepare the cars for operation, that car **A** is standing at the lower terminal floor ready for an up trip and that car **B** is standing at the upper terminal floor ready for a down trip. The closing 15 of the switch **26** for car **A** connects the driving motor **25** to a source of supply and thereby starts the generator **22** into operation. Similarly, the closing of the switch **B26** for car **B** starts the motor **B25** and a generator **B22** into operation.

20 The closing of the switch **38** connects the zone relays to the control system to limit the stop call signals to the nearest car.

The closing of the switches **27** energizes the field winding **19** of the hoisting motor **18** of car **A** and the field winding **B19** of the hoisting motor **B18** of car **B** to prepare the motors for operation. The closing of the switches **27** also energizes the up direction preference relay **W** of car **A** by a circuit extending from the supply conductor **L+1** 30 through the contact members **D5**, **X6** and **ULS** and the coil **W** to the supply conductor **L-1**, and energizes the down direction preference relay **BX** of car **B** by a circuit extending from the supply conductor **L+5** through the contact members **BU5** and **BW6** and the coil **BX** to the supply conductor **L-5** (Fig. 8).

The energization of the up direction relay **W** (for car **A**) closes its contact members **W2** thereby energizing the car button holding coils **2CC**, **3CC** and **4CC** by a circuit extending from the supply conductor **L+1** through the contact members **W7** and the coils named to the supply conductor **L-1** (Fig. 6). If any of the car buttons in car **A** are pressed by the car attendant during the 45 "up" trip they will be held in their operated condition by the energized holding coils until the car reaches the upper terminal or the direction of its operation is changed.

When the up direction preference coil **W** is energized by the closing of the contact members **X6** the electromagnet **43**, in parallel circuit with the coil **W**, is energized to tilt the arm **SM** of the floor selector from its down position to its up position, thereby causing the up brushes to engage the up contact segments for car **A**.

Inasmuch as car **A** is standing at the lower floor, its contact brush **32** is in engagement with the contact segment **a1** of the floor selector **SE**, thereby energizing the indicating stop position signal lamp **1S** by a circuit extending from the supply conductor **L+2** (Fig. 6) through the lamp **1S**, contact segment **a1**, brush **32**, conductors **61** and **62** and the contact members **N4** to the supply conductor **L-2**. The lighting of the lamp **1S** in the indicating device **59** of car **A** indicates that the position of the car is at the first floor.

Inasmuch as car **B** is at the upper terminal ready to start down, its down brush **B42** is on the down contact segment **B66** of the floor selector **BSE** (Fig. 8), thereby energizing the stop-position signal lamp **B6S** by a circuit extending from the supply conductor **L+6** through lamp **B6S**, conductor **63**, contact segment **B66**, brush **B42**, conductor **64** and contact members **BN4** to the supply conductor **L-6**. The lighting of the sig-

nal lamp **B6S** indicates that the position of car **B** is at the upper terminal.

Inasmuch as the cars are disposed at opposite terminals, the zoning brushes do not engage the zone relay contact segments, therefore none of the zone relays **2DZ**, etc. is energized.

It will now be assumed that a waiting passenger, desiring to make an up trip at the third floor, presses the up direction button **3UJ** (Fig. 7) at the third floor to give the nearest approaching up car a signal to stop at that floor. The pressing of the button **3UJ** effects the lighting of the stop call signal lamp **3L** in car **A** by energizing the call registering relay **3UR** by a circuit extending from the supply conductor **L+3** through the contact members of button **3UJ**, the coil **3UR** and conductor **74** to the supply conductor **L-3**.

The energization of the relay **3UR** closes its contact members **3UR2** to complete a self-holding circuit for itself, thereby registering the call until it is answered. The energization of the relay **3UR** also closes its contact members **3UR1** (Fig. 6) thereby energizing the stop call signal lamp **3L** by a circuit extending from the supply conductor **L+2**, through lamp **3L**, the contact members **3C1**, **W4**, **3UR1** and **2UZ1**, contact segment **b2** and brush **33** to the supply conductor **L-2**. The lighting of the lamp **3L** indicates that the attendant in car **A** should make a stop at the third floor on its up trip.

Let it also be assumed that a passenger who enters the car at the lower terminal floor asks for a fourth floor stop and that the car attendant thereupon presses the car button **4C** to register a stop call for the fourth floor. The pressing of the car button **4C** opens its contact members **4C1** and closes its contact members **4C2**, thereby lighting the stop call signal lamp **4L** in car **A** by a circuit extending from the supply conductor **L+2** through the lamp **4L**, the contact members **4C2** and conductors **66** and **67** to the supply conductor **L-2**. The car button **4C** is held in its in position after being operated, by the holding coil **4CC**.

It will now be assumed that the car attendant presses the up running push button **UP** to cause car **A** to make an up trip. The operation of the button **UP** closes its contact members **UP1** to start the car upwardly by energizing the up direction switch **U** and the inductor restoring relay **H** by a circuit extending from the supply conductors **L+1** through the contact members **UP1** and **G1**, the coil **U**, coil **H**, and the door contact members to the supply conductor **L-1**. The energization of the up direction switch **U** closes its contact members **U1**, **U2**, **U3** and **U4**.

The closing of the contact members **U4** provides a self-holding circuit for the up direction switch. The closing of the contact members **U1** energizes the brake magnet **6** thereby releasing the brake **5**. The closing of the contact members **U2** and **U3** energizes the auxiliary field winding **23** of the generator **22** by a circuit extending from the supply conductor **L+1** through the contact members **U2**, the field winding **23**, the contact member **U3** and resistors **r1** and **r2** to the supply conductor **L-1**. The release of the brake **5** and the energization of the auxiliary field winding **23** causes the generator **22** to operate the hoisting motor **18** to rotate the hoisting drum **13** and start the car upwardly.

The energization of the inductor restoring relay **H** closes its contact members **H1**, thereby energizing the intermediate speed relay **N** by a

circuit extending from the supply conductor L+1, through the contact members F1 and F2, coil N and contact members H1 to the supply conductor L-1.

- 5 The energized intermediate speed relay N closes its contact members N1, thereby short circuiting the resistor r2 in the circuit of the auxiliary field winding 23, thus causing the car to operate upwardly at its intermediate speed.
- 10 The energization of the intermediate speed relay N also opens its contact members N4 in the circuit for stop position lamp 1S for the first floor, thereby extinguishing that lamp. However, the energization of the relay N also closes its contact members N3 and thereby lights the stop position lamp 2S for the second floor by a circuit extending from the supply conductor L+2 through the lamp 2S, the contact segment a2, brush 31 and contact members N3 and V5 to the supply conductor L-2. The car is now just leaving the first floor and its stop position signal lamp 2S is lighted to indicate that, if a stop is to be made at the second floor, the car running button must be released immediately. However, no stop is to be made and the car will continue.

At this point in the operation of the car, the voltage on the generator increases to such a degree that the voltage relay K is operated to close its contact members K1 thereby completing a circuit for energizing the high speed relay V, which circuit extends from the supply conductor L+1 through the contact members UP2, E1 and E2 the coil V and the contact members K1 to the supply conductor L-1.

The energization of the high speed relay V closes its contact members V1 thereby short circuiting the resistor r1 in the circuit of the auxiliary field winding 23, thus increasing the speed of the car to its full speed.

At this instant the car has moved upwardly to such a point that it cannot now be stopped at the second floor and inasmuch as the high speed relay V has been energized, it opens its contact members V5 to deenergize the stop position signal lamp 2S for the second floor and closes its contact members V4 to energize the stop position lamp 3S for the third floor, the car having proceeded to such a point that the advance brush 30 is now on the segment a3. The circuit for the lamp 3S extends from the supply conductor L+1 through the lamp 3S, contact segment a3, brush 30 and the contact members V4 to the supply conductor L-2.

55 The lighting of the stop position lamp 3S indicates that the car running button UP should be released at once if the car is to stop at the third floor. Inasmuch as the stop call signal lamp 3L was lighted by the passenger pressing the up button 3UJ at the third floor, the car attendant now observes that the two lamps 3S and 3L are lighted side by side and this indicates to him that he should release his car switch to make a stop in answer to a call. In Fig. 2, 60 the lamps 3S and 3L are shaded to indicate the lighted condition which the car attendant observes upon now looking at the indicator device. The car attendant does not need to make any mental calculations or try to determine the position of the car or any other fact. All he needs to do is to release the car-running button whenever he observes two side by side lamps illuminated simultaneously and the car will then automatically stop at the floors for which stop signals have been given.

It will be assumed that the car attendant now releases the up running button UP thereby closing its contact members UP3 thus energizing the cancellation control relay M and the high speed decelerating inductor relay E to cancel the stop call and stop the car level with the third floor. The circuit through the relays M and E extends from the supply conductor L+1 through the contact members UP3 and DP3, to a junction point 56 where the circuit divides, one branch extending through the coil M to the supply conductor L-1 and the other branch extending through the coil E and the contact members H2 to the supply conductor L-1.

The energization of the cancellation control relay M closes its contact members M1 (Fig. 7) thereby energizing the up cancellation brush 35 for car A, and, inasmuch as that brush is now on the up contact segment d3 for the third floor, the cancellation coil 3UQ is energized by a circuit extending from the supply conductor L+3 through the contact members 3UR2, the coil 3UQ, the contact segment d3, forward brush 35 and the contact members V7 and M1 to the supply conductor L-3. The energization of the 20 cancelling coil 3UQ overcomes the energized coil 3UR thus deenergizing the registering relay 3UR and causing it to be restored to its normal condition thus cancelling the up registering stop call at the third floor as soon as the car starts 30 to answer that call.

The deenergization of the relay 3UR opens its contact members 3UR1, 3UR2, and 3UR3. The opening of the contact members 3UR1 extinguishes the stop call signal lamp 3L for the third 35 floor. The opening of the contact members 3UR2 opens the self-holding circuit for the relay 3UR. The opening of the contact members 3UR3 (Fig. 8) opens the circuit to the stop call lamp B3L in car B. However, that lamp was 40 not lighted when the contact members 3UR3 were closed because the contact members BW4 of the up direction switch of car B were open and thus no signal resulted in car B when the up call was registered at the third floor. 45

By the foregoing operation, it is seen that a registered floor call is cancelled by the first act of the car attendant in answering that call, namely releasing the car running button.

As the car continues toward the third floor, 50 the inductor relay E comes opposite the up inductor plate UE and is thereby operated to open the contact members E1 which, in turn, open the circuit for the high speed relay V and deenergize that relay.

The deenergization of the high speed relay opens its contact members V1, V2, V4 and V7 and closes its contact members V3, V5 and V6. The opening of the contact members V1 reinserts the resistor r1 in the circuit of the auxiliary field winding 23 and thereby reduces the speed of the car from high speed to intermediate speed. The opening of the contact members V2 opens the self-holding circuit for the relay V. The closing of the contact members V3 energizes the intermediate speed inductor relay F in preparation for further deceleration of the car. The opening of the contact members V4 deenergizes the brush 30 but the closing of the contact members V5 energizes the brush 31. 70 The movement of the car has now continued to such a point that the brush 30 has run off the contact segment a3 and the brush 31 has run upon the contact segment a3, thereby transferring the lighting of the lamp 3S from the brush 75

30 to the brush 31 and thus maintaining the lighting of the lamp 3S regardless of the upward movement of the car.

The opening of the contact members V1 opens 5 a circuit to the forward cancellation brush 35 and the closing of the contact members V6 transfers the cancellation circuit from the forward cancellation brush 35 to the middle cancellation brush 36 which is not disposed on the contact 10 segment d3 because the car has moved nearer to the third floor. In this manner, the cancellation coil 3UQ is maintained in an energized condition while the car is decelerated to the stop at the third floor and hence no one can again 15 register a stop call on the up third floor push button while the car is decelerating to stop at that floor.

As the car continues to approach closed to the 20 third floor, the indicator relay F passes the up inductor plate UF and is thereby operated to open its contact members F1, thus deenergizing the intermediate speed relay N, which, in turn, now opens its contact members N1, N3 and N6 and closes its contact members N2, N4 and 25 N5. The opening of the contact members N1 reinserts the resistor r2 in the circuit of the field winding 23 and thereby reduces the speed of the car from intermediate speed to stopping speed.

The closing of the contact members N2 energizes 30 the stopping inductor relay G by a circuit extending from the supply conductor L+1 through the contact members UP3, DP3 and N2, the coil G and the contact members H2 to the supply conductor L-1. The opening of the 35 contact members N3 deenergizes the brush 31 and the closing of the contact members N4 energizes the brush 32 which has now moved on to the contact segment a3. The lighting of the stop call signal lamp 3S is thereby transferred 40 from the brush 31 to the brush 32 on contact segment a3 and the lamp will remain lighted while the car comes to a stop and stays at the third floor.

The opening of the contact members N6 deenergizes 45 the middle contact brush 36 and the closing of the contact members N5 energizes the stopping brush 37 thereby transferring the circuit for the cancellation coil 3UQ from the middle brush 36 to the stopped brush 37 and inasmuch as the 50 energized brush 37 is now on the contact segment d3 because the car is close to the third floor, the cancellation coil 3UQ will remain energized while the car comes into and stops at the third floor. It will be noted that this circuit will not be re- 55 opened until the intermediate speed relay N is again energized when the car leaves the third floor. Hence, it is now seen that the cancellation coil 3UQ was energized to cancel the registered call at the third floor as soon as the car 60 attendant released the car running button and that it will remain energized while the car decelerates and stops at the third floor and until the car leaves the third floor. Therefore, when a car starts to answer a stop call at a floor, that 65 call is immediately cancelled and no new call can be re-registered until after the car completes its answer to the call and leaves the floor.

It will be assumed now that the car A approaches very close to the third floor at its stopping speed and that the stopping inductor relay G is thus brought opposite the up inductor plate UG, and is thereby operated to open its contact members G1. The opening of the contact members G1 deenergizes the up direction switch U 70 and the restoring inductor relay H.

The deenergization of the up direction switch U opens its contact members U1 thereby deenergizing the brake magnet 6; opens its contact members U2 and U3 thereby deenergizing the auxiliary field winding 23; opens its contact members U4 thereby opening its self holding circuit; and closes its contact members U5 thereby closing an interlock switch in the circuit for the down preference relay X. The deenergization of the auxiliary field winding 23 stops the hoisting motor 18 and the deenergization of the brake magnet 6 causes the application of the brake 5 to bring the car to a stop level with the third floor. 5

It will also be noted that, as the speed of the generator 22 and the motor 18 decreased, the 15 voltage on the voltage relay K dropped to such a point that the relay K opened its contact members K1 in the circuit of the high speed relay V. The relay K is now restored to its normal condition when the car is not running. 20

The deenergization of the inductor restoring relay H opened its contact members H1 and H2. The opening of the contact members H1 interlocks and prevents the energization of the speed relay N until after an up or a down direction 25 switch is energized. The opening of the contact members H2 deenergizes and restores the inductor relays E, F and G so that they will not again be energized until the car makes another run and comes to another stop. 30

The deenergization of the inductor relay E closes its contact members E1 in the circuit of the high speed relay V and thereby prepared that relay for energization when the car is again operated. The deenergization of the inductor relay 35 F closes its contact members F1 and thereby prepared the intermediate speed relay N for energization when the car is again started. The deenergization of the stopping relay G closed its contact members G1 and G2 thereby preparing 40 the up and the down direction switches and the inductor restoring relay H for operation when the car is again started.

The car is now stopped at the third floor and the car attendant opens the door (not shown) 45 thereby opening the door contact members 59.

It will be recalled that the up stop call signal lamp 4L still remains lighted indicating that a stop should be made at the fourth floor. It will now be assumed that the car attendant closes 50 the door thus closing the door contact members 59 and starts the car upwardly from the third floor by pressing the up running push button UP. The operation of the up push button energizes the up direction switch U and the inductor restoring relay H, as previously described when the car left the first floor. 55

The energized relay H recloses its contact members H2 to prepare the inductor relays for operation and closes contact members H1 to energize the intermediate speed relay N. 60

The energization of the intermediate speed relay N causes the car to increase its speed as previously described, and also opens its contact members N2, N4 and N5 and closes its contact members N3. The opening of the contact members N2 interlocks and prevents energization of the stopping inductor relay G. The opening of the contact members N5 deenergizes the brush 35. 65

The opening of the contact members N4 de- 70 energizes the brush 32 now on contact segment a3 and thereby extinguishes the stop position lamp 3S. At the same time, the closing of the contact members N3 energizes the brush 31 now on contact segment a4 thereby indicating that 75

the car running button should be released at once if the car is to stop where the next call is registered (at the fourth floor).

It may be noted here that the present system is one designed to run at moderately high speed and that consequently the deceleration of a car from high speed to a stop must be started when it is approximately eleven feet away from the floor at which the stop is to be made. Also when a car is to make only a one floor run, it must not be permitted to attain high speed after starting or it will not be able to stop at the next floor. One of the purposes of the voltage relay K is to prevent operation of the high speed relay V until the car has moved say approximately half a floor. This gives the car attendant sufficient time to start the car then operate the car controls to stop at the next floor, thus making a one floor run. The voltage relay K may be designed to operate at a voltage somewhat less than the highest voltage generated when the intermediate speed relay is in so that voltage relay K can act while the intermediate speed relay N is in to bring in the high speed relay V. Therefore, when a car is standing at a floor and a stop is to be made at the next floor, the stop position lamp for the next floor will light as soon as the car is started from the floor where it is standing so that the attendant may know to at once release the car running button before the car gets up to high speed.

In the present instance, as soon as the car attendant starts the car upwardly from the third floor stop, the stop call signal lamp 4L and the stop position lamp 4S opposite each other are lighted simultaneously side by side and the attendant, observing the two side by side lamps lighted, immediately releases the car running switch to cause the car to make a stop in response to the signal given by the lighting of the two side by side lamps. In this position of the car, it is running at intermediate speed and the high speed relay V will not be energized. Therefore, the releasing of the car switch UP now closes the circuit for energizing the intermediate speed inductor relay F, which circuit extends from the supply conductor L+1, through the contact members UP3, DP3, V3, the coil F and the contact members H2 to the supply conductor L-1. As the car continues toward the fourth floor, the inductor relay F comes opposite the inductor plate UF for the fourth floor and is thereby operated to open its contact members F1 thus deenergizing the intermediate speed relay N.

The deenergization of the intermediate speed relay N decreases the speed of the car as previously described to its stopping speed and also closes contact members N2 thereby energizing the stopping inductor relay G to stop the car when it arrives at the fourth floor.

The deenergization of the relay N also opens its contact members N3 thereby deenergizing the brush 31 now on contact segment a4, and closing contact members N4 thereby energizing the brush 32 now sliding upon the contact segment a4, thus transferring the lighting of the stop position lamp 4S from the brush 31 to the brush 32 so that the stop-position lamp will remain lighted while the car comes into and stops at the fourth floor.

As the car A decelerates to its stopping speed within about one and one-half inches of the fourth floor, the stopping inductor relay G is brought opposite the stopping inductor plate UG

for the fourth floor and is thereby operated to open its contact members G1. The opening of the contact members G1 deenergizes the up direction switch U and the inductor restoring relay H. The deenergized switch U opens its contact members U1, U2, U3 and U4 thereby deenergizing the winding 23 to stop the hoisting motor, de-energizing the brake magnet 6 to apply the brake 5 and destroying the self holding circuit for relays U and H. The deenergization of the winding 23 and the magnet 6 stops the hoisting motor 18 and applies the brake 5, thus bringing the car to a stop level with the fourth floor.

The deenergization of the inductor restoring relay H also opens its contact members H2 to deenergize the decelerating and stopping inductor relays E, F and G and prevent their reenergization until after the car is again started.

It may be noted here that as car A made the one floor run from the third floor to the fourth floor and decelerated to the stop at the fourth floor, the intermediate speed relay closed its contact members N6 (Fig. 7) in the circuit leading to the middle brush 36 as that brush engaged the contact segment d4 and then later opened those contact members and closed its contact members N5 when the circuit leading to the stopped brush 37 as that brush engaged the contact segment d4 and thereby maintained a circuit to the cancellation relay 4UQ which would prevent the registration of any stop call on the up floor button 4UJ at the fourth floor while the car was decelerating to and stopping at that floor.

It will be assumed that the car attendant now opens the door so that the passenger who desired to get off at the fourth floor may leave the car at that point.

It will be assumed that the car attendant closes the door after the passenger leaves thereby closing the door and gate contact members 59 and thus preparing the car for operation. It will also be assumed that the car attendant again presses the up running button UP thereby energizing the up direction switch U and the inductor restoring relay H, as previously described.

The energization of the switch U starts the car and the energization of the relay H closes its contact members H1 thereby energizing the intermediate speed relay N, as previously described. The energized relay N opens its contact members N4 and closes its contact members N3. The opening of the contact members N4 deenergizes the brush 32 now on the contact segment a4 for the fourth floor, thus extinguishing the stop-position lamp 4S. The closing of the contact members N4 energizes the brush 31 now on contact segment a5 thereby energizing the stop-position lamp 5S by a circuit extending from the supply conductor L+2 through the lamp 5S, the contact segment a5, brush 31 and contact members N3 and V5 to the supply conductor L-2.

As car A continues upwardly, the high speed relay V is energized and thereupon closes its contact members V4 and opens its contact members V5. As the car comes up to top speed, it can no longer stop at the fifth floor but is in position to stop at the sixth floor. Therefore, the lamp 5S is extinguished and the lamp 6S is lighted. This is accomplished by the closing of the contact members V4 energizing the brush 30 which is now on the contact segment a6 and thereby lighting the lamp 6S by a circuit extending from the supply conductor L+2 through the lamp 6S, the

contact segment *a6*, brush *30*, contact members *V4* to the supply conductor *L-2*.

As car A comes into and is stopped at the sixth floor by the usual limit switches (not shown), the high speed relay *V* is deenergized and closes its contact members *V5* and opens its contact members *V4* thus transferring the lighting of the stop position lamp *6S* from the brush *30* to the brush *31*. As the car comes still closer to the sixth floor, the intermediate speed relay *N* is deenergized thus closing its contact members *N4* and opening its contact members *N3*. The opening of the contact members *N3* deenergizes the brush *31* and the closing of the contact members *N4* energizes the brush *32* now on the contact segment *a6*, thereby transferring the lighting of the lamp *6S* from the brush *31* to the brush *32* so that the lamp *6S* will remain lighted as the car comes into and stops at the sixth floor.

When car A arrives at the upper terminal, its upper limit switch *ULS* is operated to open the circuit of the up direction preference relay *W* thereby deenergizing that relay to open its contact members *W1*, *W2*, *W3*, *W4* and *W5* in the circuits of the stop call signal lamps *2L*, *3L*, *4L*, *5L* and *6L*, thereby rendering the up contact segments *b2*, *b3*, *b4*, *b5* and *b6* ineffective while the car is making its down trip. The deenergized relay *W* also closes its contact members *W6* and opens its contact members *W7*.

The opening of the contact members *W7* deenergizes the car button holding coils *2CC*, *3CC*, *4CC* and *5CC*, thereby restoring to normal condition the car button *3C* on car A which was operated by the car attendant to signal an up stop at the third floor on the up trip.

The closing of the contact members *W6* energizes the down direction preference relay *X* of car A by a circuit extending from the supply conductor *L+1* through the contact members *U5*, *W6* and *DLS*, and the relay *X* to the supply conductor *L-1*.

When the down direction preference relay *X* is energized, the electromagnet *49* in parallel therewith is energized to tilt the floor selector arm *SM* from its up position to its down position thereby causing the down brushes to engage the down contact segments of car A.

The energization of the down direction relay *X* closes its contact members *X1*, *X2*, *X3*, *X4* and *X5*, thereby connecting the stop call signal lamps *1L*, *2L*, *3L*, *4L* and *5L* in car A to their contact segments *f1*, *f2*, *f3*, *f4* and *f5* for down direction operation, so that the stop call signal lamps in car A may be operated by either the push buttons in the car or at the floors for down direction operation.

The energization of the down direction relay *X* also closes its contact members *X7*, thereby again energizing the car button holding coils *2CC*, *3CC*, *4CC* and *5CC*. If any of the car buttons in car A are pressed by the car attendant during the down trip, they will be held in their operated condition by the energized holding coils until the car reaches the lower terminal where the direction of its operation is changed.

By the foregoing operation, it is seen that pressing of either a car signal button or a floor signal button will cause the operation of signal lamps in the car in such manner as to indicate to the car attendant when to release the car switch to automatically stop the car level with the floors for which the signal buttons have been operated. Therefore, it is evident that with this system

it is unnecessary for the car attendant to do anything after starting the car, except watch the indicating device and release the car running push button for such stops as are to be made when they show up on the indicating device.

5

Cars A and B are now standing at the upper terminal and each car is ready for a down trip. Inasmuch as car B has been waiting with its door open, it will be assumed that a passenger boards car B and that the attendant in car B closes the door (not shown), thereby closing the door contact members *B59*, and presses the car running button *BDP* to run the car downwardly.

The pressing of the push button *BDP* closes its contact members *BDP1* and *BDP2* and opens its contact members *BDP3*. The opening of the contact member *BDP3* prevents energization of the deceleration and stopping inductor relays *BE*, *BF* and *BG* until the running button *BDP* is released to stop car B. The closing of the contact members *BDP2* prepares the high speed relay *BV* for energization.

The closing of the contact members *BDP1* energizes the down direction switch *BD* by a circuit extending from the supply conductor *L+5* through the contact members *BDP1* and *BG2*, the direction switch *BD*, the inductor restoring relay *BH* and the door contact members *B59* to the supply conductor *L-5*. The energized down direction switch *BD* closes its contact members *BD1*, *BD2*, *BD3*, and *BD4* and opens its contact members *BD5*. The closing of the contact members *BD1* energizes the brake magnet *B6* by a circuit extending from the supply conductor *L+5* through the contact members *BD1* and the magnet *B6* to the supply conductor *L-5*. The closing of the contact members *BD2* and *BD3* energizes the auxiliary field winding *B23* by a circuit extending from the supply conductor *L+5* through the contact members *BD3*, the winding *B23*, the contact members *BD2* and the resistors *Br1* and *Br2* to the supply conductor *L-5*. The closing of the contact members *BD4* establishes a self-holding circuit for the down direction switch *BD*. The opening of the contact members *BD5* provides an interlock in the circuit of the up direction preference relay *BW*.

The energization of the field winding *B23* and the brake magnet *B6* causes the release of the brake *B5* and the energization of the hoisting motor *B18* to move the car B downwardly.

The energization of the inductor restoring relay *BH* closes its contact members *BH1* and *BH2*. The closing of the contact members *BH2* prepares the stopping inductor relays *BE*, *BF* and *BG* for energization when it is desired to stop car B and the closing of the contact members *BH1* energizes the intermediate speed relay *BN* by a circuit extending from the supply conductor *L+5* through the contact members *BF1* and *BF2*, the relay *BN* and the contact members *BH1* to the supply conductor *L-5*.

The energization of the intermediate speed relay *BN* opens its contact members *BN1*, *BN4* and *BN5* and closes its contact members *BN2*, *BN3* and *BN6*. The closing of the contact members *BN3* short circuits the resistor *Br2* in the circuit of the field winding *B23* and thereby causes the car to operate at its intermediate speed. The opening of the contact members *BN1* prevents cancellation of a call while car is running at intermediate speed without answering a call and the closing of the contact members *BN2* prepares to cancel a call received.

The opening of the contact members *BN4* deenergizes the down brush *B42* now on the con-

75

tact segment **B6** thereby extinguishing the stop-position lamp **B5S** for the floor which the car is leaving, and the closing of the contact members **BN6** energizes the brush **B41** now on contact segment **Be5** thereby lighting the stop-position lamp **B5S** for the next floor by a circuit extending from the supply conductor **L+6** (Fig. 8) through the lamp **B5S**, conductor **65**, the contact segment **Be5** and brush **B41** and contact members **BN6** and **BV7**. The stop-position lamp **B5S** is lighted to indicate that if a stop is to be made, at the fifth floor, the car button must be now released. However, inasmuch as no stop is indicated by the stop call signal lamp **B5L**, the car attendant does not release the car running push button.

As car **B** continues to move downwardly from the upper terminal, say one-half floor, the generator voltage increases to the predetermined point where the voltage relay **BK** is operated to close its contact members **BK1**, thereby energizing the high speed relay **BV** to close its contact members **BV2**, **BV3**, **BV4** and **BV6** and open its contact members **BV1**, **BV5** and **BV7**. The closing of the contact members **BV3** short circuits the resistor **Br1** in the circuit of the field winding **B23** and thereby causes the car to run at its normal high speed. The closing of the contact members **BV4** establishes a self-holding circuit for the high speed relay **BV**. The opening of the contact members **BV5** prevents energization of the intermediate speed inductor relay **BF** until the intermediate speed relay **BV** is again de-energized.

The opening of the contact members **BV7** de-energizes the brush **B41** and the closing of the contact members **BV6** energizes the brush **B40**, which is now on the contact segment **Be4** by reason of the downward movement of car **B**, and in such position energizes the stop position lamp **B4S** by a circuit extending from the supply conductor **L+6** through lamp **B4S**, conductor **76**, the contact segment **Be4**, brush **B40** and the contact members **BV6** to the supply conductor **L-6**. Inasmuch as the stop call lamp **B4L** is not lighted, the attendant makes no move to stop the car, even though the stop position indicating lamp is lighted. As the car moves on downwardly, the advance brush **B40** leaves the contact segment **Be4**, thereby extinguishing the lamp **B4S** and engages the contact segment **Be3**, thereby lighting the lamp **B3S**, thus indicating that if a stop is to be made at the third floor, the car running button should be released immediately. However, inasmuch as the stop call lamp beside the lighted stop position lamp is not lighted, the attendant makes no move to stop the car.

With car **A** standing at the upper terminal ready to go down and with car **B** traveling downward and just passing the fourth floor and approaching within stopping distance of the second floor (which is approximately a little more than one and one-half floors above the second floor), it will be assumed that a waiting passenger at the second floor, desirous of going down, presses the down button **2DJ** and thereby lights the stop call signal **B2L** in car **B**, but does not light the similar stop call signal **2L** in car **A**. Under these conditions as car **B** continues on down, it will come to the point where the stop-position lamp **B2S** and the stop-call lamp **B2L** will be lighted simultaneously in side-by-side position, and the operator observing them will release the car running button and thus stop the car at the second floor to take on the waiting passenger.

The pressing of the floor button **2DJ** ener-

gizes the registering relay **2DR** by a circuit extending from the supply conductor **L+3** through the contact members of the push button **2DJ**, the relay **2DR** and the conductor **64** to the supply conductor **L-3**. The energization of the registering relay **2DR** closes its contact members **2DR1**, **2DR2** and **2DR3**. The closing of the contact members **2DR2** completes a self-holding circuit for the relay **2DR**. The closing of the contact members **2DR3** lights the stop-call lamp **B2L** in car **B**, by a circuit extending from the supply conductor **L+6** through the lamp **B2L**, the contact members **B2C1**, conductor **67**, contact members **BX4**, **2DR3** and **3DZ2**, contact segment **Bf3**, and brush **B43**, to the supply conductor **L-6**.

The closing of the contact members **2DR1** in the circuit leading to the stop call lamp **2L** in car **A** (Fig. 6) fails to light that lamp because of the operation of the zone relays. Hence the stop call at the second floor is restricted to lighting the stop-call signal lamp in only the nearest approaching car.

The following explanation of the zone relays will disclose how a registered floor call lights the corresponding stop call lamp in only the nearest approaching car and does not light the stop call lamps in the other approaching cars. For instance, car **B** and car **A** are both approaching the stop call at the second floor, but the stop call in car **B** is lighted while the stop call lamp in car **A** corresponding to the second floor is not lighted.

With car **A** standing at the upper terminal ready for a down trip, its zone brush **44** is not in engagement with any of the zone contact segments **g**, therefore car **A** does not operate any of the zone relays **5DZ**, **4DZ**, etc.

However, with car **B** at the fourth floor on its down trip, its zone brush **B44** is in engagement with the contact segment **Bg4** thereby energizing the zone relay **4DZ** by a circuit extending from the supply conductor **L+3** through the zone relay **4DZ**, the contact segment **Bg4** and brush **B44** to the supply conductor **L-4**.

The energization of the zone relay **4DZ** opens its contact members **4DZ1** in the circuit to the stop-call lamps in car **A** (Fig. 6) and opens its contact members **4DZ2** (Fig. 8) in the circuits leading to the stop-call lamps in car **B**. By referring to the circuits for the stop-call lamps in car **B**, it will be seen that the opening of the contact members **4DZ2** has no effect on the circuit already established for energizing the stop-call lamp **B2L** in car **B**, inasmuch as that circuit extends from brush **B43** through contact segment **Bf3** as car **B** passes the fourth floor and thence through the closed contact members **3DZ2**, etc., as heretofore described. By referring to the circuit for car **A**, it will be seen that with car **A** standing at the upper floor ready for a down trip, although its down brush **43** engages the contact segment **f5** for the fifth floor, no current can be supplied through it to the stop-call lamp **2L** in car **A**, even though the contact members **2DR1** of the registering relay **2DR** have been closed in the circuit leading to the lamp **2L**, because the zone contact members **4DZ1** are open.

In this manner, it will be seen that the zone relays operated by the zone brushes **34** and **44** of car **A** and **B34** and **B44** of car **B** prevent the lighting of the stop call lamps except in the car nearest the registered stop call.

As car **B** passes the fourth floor, its brush **B40** engages the down contact segment **Be2** and thereby lights the stop-position indicating lamp **B2S** by a circuit extending from the supply con-

ductor L-6 through the lamp B2S, conductor 68, contact segment Be2, brush B40 and the contact members BV6 to the supply conductor L-6.

Inasmuch as the lighted stop position lamp B2S is side-by-side with the lighted stop call lamp B2L, the attendant observes this signal and immediately releases the car button BDP to throw into operation the automatic inductor relay stopping system to stop the car level with the second floor.

The releasing of the running button BDP opens its contact members BDP1 and BDP2 and closes its contact members BDP3. The opening of the contact members BDP1 and BDP2 in the circuits of the down direction switch BD and the intermediate speed relay BU has no effect because this switch and this relay have established self-holding circuits for themselves. However, the closing of the contact members BDP3 energizes cancellation control relay BM and the high speed inductor relay BE.

The circuit for energizing the relays BM and BE extends from the supply conductor L-5 (Fig. 8) through the contact members BUP3 and BDP3 to a junction point 57 where it divides, one branch extending through the coil BM to the supply conductor L-5 and the other branch extending through the coil BE and the contact members BH2 to the supply conductor L-5.

The energization of the relay BM closes its contact members BM1 thereby energizing the down cancellation brush B45 of car B so that, as that brush engages the contact segment Bh2, it thereby energizes the cancellation coil 2DQ by a circuit extending from the supply conductor L-3 through the contact members 2DR2, coil 2DQ conductor 69, contact segment Bh2, brush B45 and the contact members BV2 and BM1 to the supply conductor L-4. The energized coil 2DQ on the relay 2DR overcomes the energized relay and causes it to open its contact members 2DR1 in the circuit to the stop call lamp 2L in car A, to open its contact members 2DR2 in its own self-holding circuit, and to open its contact members 2DR3 in the circuit of the stop-call lamp B2L in car B, thereby restoring the registering relay 2DR to its original condition.

As car B continues downwardly, the energized high speed inductor relay BE passes the down high speed inductor plate BDE and is thereby operated to open its contact members BE2 thereby deenergizing the high speed relay BV to open its contact members BV2, BV3, BV4 and BV6 and close its contact members BV1, BV5 and BV7. The opening of the contact members BV3 reinserts the resistor Br1 in the circuit of the field winding B23 thereby decelerating the car to its intermediate speed. The opening of the contact members BV4 opens the self-holding circuit for the relay BV. The closing of the contact members BV5 energizes the intermediate speed inductor relay BF.

The car has now been reduced to intermediate speed and the opening of the contact members BV6 and the closing of the contact members BV7 deenergizes the brush B40 and energizes the brush B41, thereby transferring the lighting of the stop-position lamp B2S from advance brush B40 to intermediate brush B41, the car having now moved forward to a point where brush B41 is on the contact segment Be2, thus transferring the lighting of the stop-position lamp B2S from one brush to the other and maintaining it lighted while the car is decelerating.

The opening of the contact members BV2 and the closing of the contact members BV1 transfers the cancellation circuit from the forward brush B45 to the middle brush B46 and inasmuch as the brush B46 is now on the contact segment Bh2, the cancellation of coil 2DQ remains energized and thereby prevents any down stop call being registered at the second floor while car B is decelerating to a stop at that floor.

As car B approaches still closer to the second floor, the energized intermediate speed inductor relay BF comes opposite the inductor plate BDF and is operated to open its contact members BF2, thereby deenergizing the intermediate speed relay BN to close its contact members BN1, BN4 and BN5 and open its contact members BN2, BN3 and BN6.

The opening of the contact members BN3 reinserts the resistor Br2 in the circuit of the field winding B23 and thereby decreases the speed of the car to the stopping speed.

The closing of the contact members BN5 of the deenergized relay BN energizes the stopping inductor relay BG to effect the stopping of the car at the second floor.

The opening of the contact members BN6 deenergizes the intermediate brush B41 and the closing of the contact members BN4 energizes the standing brush B42, thereby transferring the lighting of the stop-position lamp B2S in car B from brush B41 to brush B42, which now, by reason of the near approach of the car to the second floor, is in engagement with the contact segment Be2. Therefore, the lamp B2S is lighted and will remain lighted while car B comes into and stands at the second floor. Thus, it is seen that the lighting of the lamp B2S not only indicates when the car running button should be released to make the cap stop, but also indicates the floor for which the car is decelerating and also the floor at which the car stands after decelerating to a stop.

The opening of the contact members BN2 and the closing of the contact members BN1 transfers the cancellation circuit from the middle brush B46 to the stopped brush B45, now on contact segment Bh2 thus maintaining the cancellation coil 2DQ in an energized condition while the car comes in and stops at the floor and thereby prevents any one from registering a down stop call while car B comes into and stops at the second floor.

As car B decelerates to within a few inches of the second floor, the stopping inductor relay BG comes opposite the down inductor plate BDG and is thereby operated to open its contact members BG2, thereby deenergizing the down direction switch BD, which in turn opens its contact members BD1, BD2, BD3 and BD4.

The opening of the contact members BD1 deenergizes the brake magnet B6 to apply the brake B5. The opening of the contact members BD2 and BD3 deenergizes the auxiliary field winding B23. The simultaneous deenergization of the winding B23 and the application of the brake B5 causes the car B to stop level with the second floor, so that the car attendant may open the car doors (not shown) to permit the waiting passenger at the second floor to enter the car.

By reason of the foregoing operation, it is seen that when a plurality of cars are approaching a floor at which a stop signal push button for their direction of operation has been pressed, the zoning system operates to restrict the stop

signal to only the nearest approaching car, and that no stop signal is given in the more distant approaching car. This matter of giving the stop signal in only the nearest approaching car saves needless operation of the stop-call signal lamps, because, if the bank of elevator cars, say 5 or 6 cars traveling in the same direction, a stop call signal lamp would be lighted in every car instead of in only one car, if no zoning means were employed. The needless lighting of the signal lamps in the more distant cars would cause the lamps to wear out and become useless more rapidly. It would also cause confusion in the operation of the cars because it usually takes some time to discover that a signal lamp is not functioning. It is also evident that the frequent renewal of lamps costs both time and money. Therefore, my system which will prevent the needless operation of lamps will effect a considerable saving.

In the system so far disclosed, each of the stop-call signal lamps 2L, 3L, etc. is operated by a single lamp bulb 70 (Fig. 3), the lighting of which is controlled by either the floor button or the car stop call button. In some elevator installations however, it may be desirable to use two lamp bulbs instead of one in each of the stop call signal lamps 2L, etc., and have one bulb operated by the floor button and the other bulb operated by the car button.

In Fig. 9, we have illustrated a circuit for the stop-call signal lamps of car A similar to that shown in the upper right hand corner of Fig. 6, except that the wiring is slightly different so that the pressing of a car signal button will light one lamp bulb and the pressing of the floor button will light another lamp bulb, but both bulbs will illuminate the same target. Referring more particularly to Fig. 9, it will be observed that the stop call signal lamp 2L comprises the usual target 52 as shown in Figs. 10 and 11, and also two lamp bulbs 71 and 72. The two bulbs 71 and 72 are placed in the same compartment behind the target 53 so that they and the target comprise the lamp 2L. Referring to Fig. 9, it will be observed that the circuit for the bulb 71 extends from the supply conductor L+7 through lamp 71, push button 2C and circuit 73 to the supply conductor L-7. Hence, it will be seen that the lamp 71 may be lighted by pressing the car push button 2C. The circuit for the lamp 72 extends from supply conductor L+7 through the contact members W5 and 2UR1 to the contact segment b2 and thence through the brush 33 to the supply conductor L-7, when the car is going in the up direction. When the car is going in the down direction the circuit for the lamp 72 extends from the supply conductor L+7 through the lamp 72, conductor 75, the contact members X4 and 2DR1, the contact segment f2 and brush 43 to the supply conductor L-7. When either the lamp 71 is lighted by operation of the button 2C or lamp 72 is lighted by operation of the floor button, the target 53 will be illuminated to indicate a stop call.

Hence, it will be readily seen that our system may be easily modified to include separate incandescent lamp bulbs for the floor circuits and the car signal button circuits instead of single incandescent bulbs operating on both circuits, and if a single target is placed over both incandescent bulbs when two are used, the effect will be the same as when a single incandescent bulb is used. On the other hand, if the target is left off and the incandescent bulbs employed in lieu of the target

are aligned with the stop indicating lamp, at the third floor, for instance, the operator will receive his stop signals when aligned stop call lamps and stop position lamps are lighted.

When desired, the system may be operated without the use of the zone relays, by opening the switch 38 in the circuit leading from the supply conductor L+3 (Fig. 7) to the up zone relays and the down zone relays 5DZ etc. It will be assumed now that this switch is opened, that car A is run down to the lower terminal and back up to and stopped at the third floor on its up trip, and that car B is run to the lower terminal and is left standing there ready for an up trip. It will also be assumed that a waiting passenger at the fifth floor, desiring to make an up trip, presses the up push button 5UJ at that floor. The operation of the button 5UJ causes an up stop call signal for the fifth floor to be given in each of cars A and B. The closing of the button 5UJ energizes the call registering relay 5UR by a circuit extending from the supply conductor L+3 through the contact members of button 5UJ and the coil of relay 5UR to the supply conductor L-3. The energization of the relay 5UR closes its contact members 5UR1, 5UR2 and 5UR3.

The closing of the contact members 5UR2 provides a self holding circuit for the registering relay which maintains the up stop call at the fifth floor in registered condition until some car stops in answer to it.

The closing of the contact members 5UR1 (Fig. 6) lights the up stop call lamp 5L for the fifth floor in car A by a circuit extending from the supply conductor L+2 through the lamp 5L, 35 the contact members 5C1, W2, 5UR1, 4UZ1, 3UZ1, contact segment b3 and brush 33 to the supply conductor L-2. The lighted stop call lamp 5L in car A will remain lighted until the call is cancelled or until the car passes beyond the fifth 40 floor.

The closing of the contact members 5UR3 (Fig. 8) lights the stop call lamp B5L in car B by a circuit extending from the supply conductor L+6 through the lamp B5L, contact members 45 B5C1, BW2, 5UR3, 4UZ2, 3UZ2, and 2UZ2, the contact segment Bb2 and brush B33 to the supply conductor L-6. The circuit passes through the contact segment Bb2 because brush B33 is on the contact segment for the second floor even 50 though car B is standing at the first floor ready for an up trip.

By the foregoing, it is seen that when the zone relays are not connected to the circuit, their contact members in the circuits for the stop 55 call lamps in the cars remain closed and thus cause the operation of the floor button at a floor to light the stop call signal lamp corresponding to that floor in each car operating in that direction. 60

It will be understood by the foregoing that by means of the switch 38, the system may be easily controlled to be operated either as a means for causing the lighting of stop signal lamps in every car travelling in the corresponding direction or as a system in which the lighting of the stop signal lamp in response to the operation of a floor button will be restricted to only the nearest approaching car for the floor and the direction of operation of the operated floor 70 button.

By reason of the foregoing description, it will also be seen that we have provided a signal system which may be easily and economically installed, operated and maintained and one which 75

will relieve the car attendants of much unnecessary mental work in operating their cars.

Although we have shown and described only one form of our invention with a slight modification thereof, it is to be understood that many changes and modifications of the system may be made without departing from the spirit and scope of our invention.

We claim as our invention:

- 10 1. In an elevator system for operating a car past a floor, means for starting, running and stopping the car, a signal device in the car, means responsive only to the approach of the car to the floor for operating the signal device only while the car can yet be operated to stop at the floor to indicate when the means for stopping the car should be operated to cause it to stop at the floor, and means responsive to deceleration of the car for a stop at the floor for operating said signal device to indicate the floor to which said car is decelerating to a stop.
- 15 2. In an elevator system for operating a car past a floor, means for starting, running and stopping the car, a signal device in the car, means responsive to the approach of the car to the floor for operating the signal device only while the car can yet be operated to stop at the floor to indicate when the means for stopping the car should be operated to cause it to stop at the floor, means responsive to deceleration of the car to a stop at the floor for operating said signal device to indicate the floor for which the car is decelerating to a stop, and means responsive to the standing of the car at the floor for operating the signal device to indicate the floor at which the car is standing.
- 20 3. In an elevator system for operating a car past a plurality of floors, a plurality of signal devices on the car, one for each floor, and means responsive to operation of the car for operating said signal device for each floor while the car is in position to make a stop at that floor, while the car decelerates to a stop at that floor, and while the car stands at that floor.
- 25 4. In an elevator system having a car operable past a floor, means for operating the car, means for controlling the operating means to run the car at high speed, means for controlling the operating means to run the car at intermediate speed, means for controlling the operating means to stop the car at the floor, a floor selector comprising a contact segment and an advance brush, an intermediate brush and a standing brush, means responsive to movement of the car for moving the brushes into sequential engagement with the contact segment in accordance with the position of the car as the car approaches the floor, a signal device on the car corresponding to the floor, a circuit for said signal device, said circuit including parallel circuits through the brushes, for connecting the circuit to a source of power, means responsive to operation of the high speed control means when the car approaches within a predetermined distance of the floor for connecting said circuit to the advance brush, means responsive to operation of the intermediate speed control means when the car approaches within a predetermined distance of the floor for connecting said circuit to the intermediate brush, and means responsive to the stopping control means for connecting said circuit through the standing brush when the car is standing at the floor, to cause the signal device to indicate when the control means should be operated to stop the car at the floor, the floor

at which the car will stop and the floor at which the car stands.

5. In an elevator system having a car operable past a floor, means for operating the car, means for controlling the operating means to run the car at high speed, means for controlling the operating means to stop the car at the floor, a floor selector comprising a contact segment, an advance brush and a standing brush, means responsive to movement of the car for moving the brushes into sequential engagement with the contact segment in accordance with the position of the car on its approach to the floor, a signal device on the car corresponding to the floor, a circuit for said signal device, said circuit including parallel circuits through the brushes, means for connecting the circuit to a source of power, means responsive to operation of the high speed control means when the car approaches within a predetermined distance of the floor for connecting said circuit to the advance brush, and means responsive to operation of the stopping control means for connecting said circuit through the starting brush when the car is standing at the floor, to cause the signal devices to indicate when the control means should be operated to stop the car at the floor and to indicate the floor at which the car stands after it stops.

6. In a signal system for an elevator car operable past a floor, a stop call signal device on the car, means including a switch at the floor for operating the stop call signal device to indicate that the car should stop at the floor, and a stop position signal device on the car responsive to the approach of the car to the floor for indicating that the car is within stopping distance of the floor, said stop call signal device and said position signal device being disposed adjacent to each other to indicate by their simultaneous operation when the car should be operated to stop in answer to a stop call at the floor.

7. In a signal system for an elevator car operable past a floor, a stop call signal device on the car, means including a switch at the floor for operating the stop call signal device to indicate that the car should stop at the floor, a stop position signal device on the car, and means responsive to the approach of the car to the floor for operating the position signal device to indicate when the car is within stopping distance of the floor, said stop call signal device and said stop position signal device being disposed adjacent to each other on the car to indicate by their simultaneous operation when the car attendant should operate the car to answer a stop call.

8. In an elevator system for operating a car past a floor, a control device on the car for causing the car to stop at the floor, a stop call signal device on the car, means including a switch at the floor for operating the stop call signal device to indicate that the car should stop at the floor, a stop position signal device on the car, and means responsive to the approach of the car to the floor for indicating when the car is within stopping distance of the floor, said call signal device and said position signal device being disposed adjacent to each other to indicate by their simultaneous operation when the car attendant should move the control device to car stopping position to answer a stop call.

9. In a signal system for an elevator car operable past a plurality of floors, a plurality of stop call signal devices on the car, one for each floor, a switch at each floor for operating the stop call signal device corresponding to that floor to indi-

cate that the car should stop at that floor, a plurality of stop position signal devices on the car, one for each floor, means responsive to the approach of the car to each floor for operating 5 the stop position signal device corresponding to that floor to indicate when the car is within stopping distance of that floor, said stop call signal devices being mounted in a row and said stop position signal devices being mounted in a 10 row and said rows being disposed on the car with the stop position signal device and the stop call signal device for each floor in alignment with each other whereby their simultaneous operation will indicate to the car attendant that he should immediately operate the car to answer a stop call.

10. In an elevator system for operating a plurality of cars past a plurality of floors, a control device on each car for causing the car to stop, 20 a plurality of stop signal devices on each car, one for each floor, a switch at each floor, means responsive to operation of the switch at a floor for operating the stop call signal device on each car for that floor, a stop position signal device 25 on each car for each floor, means responsive to the approach of each car within a predetermined distance of each floor for operating the stop position signal device in that car for that floor to indicate that that car is within stopping 30 distance of that floor, the stop call signal device and the stop position signal device for each floor on each car being disposed adjacent to each other to indicate by their simultaneous operation that the control device should be immediately moved 35 to car stopping position to answer a stop call.

11. In an elevator system for operating a plurality of cars past a plurality of floors, a stop call signal device on each car for each floor, a switch at the floor, means responsive to operation of a switch at a floor and to the operation of the cars for operating the stop call signal device for the corresponding floor on only the nearest approaching car to that floor, a stop position signal device on each car for each floor, means 45 responsive to the approach of each car to each floor for operating the position signal device on that car for that floor to indicate that the car is within stopping distance of that floor, said stop call signal devices and stop position signal 50 devices being placed in parallel rows in the cars with the signal devices for each floor in alignment with each other whereby the simultaneous operation of aligned signal devices in a car will indicate that the car should be immediately operated to answer a stop call.

12. In a signal device for an elevator car operable past a floor, a stop call signal device on the car, means including a switch on the car for operating the stop call signal device to indicate 60 that the car should stop at the floor, and a stop position signal device on the car responsive to the approach of the car to the floor for indicating when the car is within stopping distance of the floor, said stop call signal device and said 65 position signal device being disposed adjacent to each other to indicate by their simultaneous operation when the car attendant should operate the car to answer a stop call.

13. In a signal system for an elevator car operable past a floor, a stop call signal device on the car, means including a switch on the car for operating the stop call signal device to indicate that the car should stop at the floor, a stop position signal device on the car, and means responsive to the approach of the car to the floor 70

for operating the position signal device to indicate when the car is within stopping distance of the floor, said stop call signal device and said stop position signal device being disposed adjacent to each other on the car to indicate by their 5 simultaneous operation the time when the car attendant should operate the car to answer a stop call.

14. In an elevator system for operating a car past a floor, a control device on the car for stopping the car, a stop call signal device on the car, means including a switch on the car for operating the stop call signal device to indicate that the car should stop at the floor, a stop position signal device on the car, and means responsive 15 to the approach of the car to the floor for indicating when the car is within stopping distance of the floor, said call signal device and said position signal device being disposed adjacent to each other to indicate by their simultaneous opera- 20 tion when the car attendant should move the control device to car stopping position for answering a stop call.

15. In a signal control system for an elevator car operable past a plurality of floors, a plurality 25 of stop call signal devices on the car, one for each floor, a plurality of switches on the car, one for each floor, for operating the stop call signal device for that floor to indicate that the car should stop at that floor, a plurality of stop 30 position signal devices on the car, one for each floor, and means responsive to the approach of the car to each floor for operating the stop position signal device corresponding to that floor to indicate when the car is within stopping dis- 35 tance of that floor, said stop call signal devices being mounted in a row and said stop position signal devices being mounted in a row and said rows being disposed with the stop signal device and the stop call signal device for each floor in 40 alignment with each other whereby their simultaneous operation will indicate to the car attendant that he should immediately operate the car to answer a stop call.

16. In an elevator system for operating a plurality of cars past a plurality of floors, a control device on each car for stopping it, a plurality of stop signal devices on each car, one for each floor, a plurality of switches on each car one for each floor, means responsive to operation of a 50 switch for a floor in a car for operating the corresponding stop call signal device on the car for the floor, a stop position signal device on each car for each floor, means responsive to the approach of each car within a predetermined dis- 55 tance of each floor for operating the stop position signal device in that car for that floor to indicate that that car is within stopping distance of the floor, the stop call signal device and the stop position signal device for each floor on each car 60 being disposed adjacent to each other to indicate by their simultaneous operation that the control device should be immediately moved to car stopping position to answer a stop call.

17. In a signal device for an elevator car operable past a floor, a switch at the floor, a switch in the car for the floor, a signal device in the car operably responsive to operation of the floor switch or the car switch for indicating that the car will stop at the floor, a stop position signal 70 device on the car, and means responsive to the approach of the car to the floor for operating the position signal device to indicate when the car is within stopping distance of the floor, said stop call signal device and said stop position sig- 75

nal device being disposed adjacent to each other on the car to indicate by their simultaneous operation when the car attendant should operate the car to answer a stop call at the floor.

- 5 18. In an elevator system for operating a car past a floor, a control device on the car for stopping it, a switch at the floor and a switch in the car for the floor, a stop call signal device in the car responsive to operation of either the floor 10 switch or the car switch for indicating that the car should stop at the floor, a stop position signal device on the car, and means responsive to the approach of the car to the floor for operating the stop position signal device to indicate when the 15 car is within stopping distance of the floor, said call signal device and said position signal device being disposed adjacent to each other to indicate by their simultaneous operation when the control device should be moved to car stopping 20 position to answer a stop call.
19. In a signal system for an elevator car operable past a plurality of floors, a plurality of floor switches, one at each floor, a plurality of car switches in the car, one for each floor, a plurality of stop call signal devices on the car, one for each floor, means responsive to operation of a floor switch or a car switch for operating the stop call signal device for that floor to indicate the existence of a stop call at that floor, a plurality of stop position signal devices on the car, one for each floor, means responsive to the approach of the car to each floor for operating the stop position signal device corresponding to that floor to indicate when the car is within stopping 30 distance of that floor, said stop call signal devices being mounted in a row and said stop position signal devices being mounted in a row, said rows being disposed on the car with the stop position signal device and the stop call signal device 35 for each floor in alinement with each other to indicate by their simultaneous operation when the car attendant should operate the car to answer a stop call.

20. In an elevator system for operating a plurality of cars past a plurality of floors, a control device on each car for causing that car to stop, a switch at each floor common to all the cars, a plurality of switches in each car one for each floor, a plurality of stop signal devices on each 45 car one for each floor, means responsive to operation of a switch at a floor for operating the corresponding stop call signal device on each car for that floor, means responsive to operation of a

switch in a car for a floor for operating the corresponding stop call signal device in that car for that floor, a stop position signal device on each car for each floor, means responsive to the approach of each car within a predetermined distance of each floor for operating the stop position signal device on that car for that floor to indicate that that car is within stopping distance of that floor, the stop call signal device and the stop position signal device for each floor on each car 10 being disposed adjacent to each other to indicate by their simultaneous operation that the control device should be immediately moved to car stopping position to answer a stop call.

21. In an elevator system for operating a plurality of cars past a plurality of floors, a switch at each floor common to all the cars, a plurality of switches in each car one for each floor, a plurality of stop call signal devices in each car, one for each floor, means responsive to operation of a switch at a floor and to the operation of the cars for operating the stop call signal device for the corresponding floor of only the nearest approaching car to that floor, means responsive to operation of a switch in a car for operating the stop call signal device in that car for that floor to indicate the existence of a stop call at that floor, a stop position signal device on each car for each floor, and means responsive to the approach of each car within a predetermined distance of each 20 floor for operating the position signal device on that car for that floor to indicate that the car is within stopping distance of that floor, said stop call signal devices and stop position signal devices being placed in parallel rows in the cars with the signal devices for each floor in alinement with each other whereby the simultaneous operation of alined signal devices in a car will indicate that the car should be immediately operated to answer a stop call.

22. In an elevator system for operating a car past a floor, means for starting, running and stopping the car, a signal device in the car, means responsive to the approach of the car to the floor for operating the signal device only while the car can 45 yet be operated to stop at the floor to indicate when the means for stopping the car should be operated to cause it to stop at the floor, and means responsive to the standing of the car at the floor for operating the signal device to indicate the 50 floor at which the car is standing.
